ORDNANCE

Gregory C. Davison, Lyme, Conn.; Alice Lydia Shepard Davison, executrix of said Gregory C. Davison, deceased, assignor, by mesne assignments, to American Ordnance Corporation, New London, Conn., a corporation of Delaware

Application April 7, 1934, Serial No. 719,465

12 Claims.

(Cl. 89—43)

This invention relates to ordnance and particularly to recoil and counter-recoil or running-out gear for guns.

More particularly stated, the invention relates to mechanism of the hydro-pneumatic type utilizing both liquid and gas to take up the recoil and return the gun to battery position after firing. The mechanism employs a pneumatic recuperator which is initially filled with gas under a predetermined pressure. This gas is compressed during the recoil operation and in turn furnishes the force to return the gun and parts connected thereto to battery position.

The firing of the gun causes the development of very high hydraulic pressures in the system and in most of the designs of the hydro-pneumatic type these pressures are communicated to all parts of the system giving rise to leakage in the packings and stuffing boxes.

This invention has for one of its objects to provide a hydro-pneumatic recoil and counter-recoil system and mechanism so designed as to confine the high pressures to the recoil cylinder and to prevent the communication of such high pressures to other parts of the mechanism and system.

Another object of the invention is to provide mechanism of the character described so constructed and arranged as to obtain a positive control of the counter-recoil and furthermore a construction in which the recoil and counter-recoil actions are positive and independent of the amount of fluid in the recuperator or of the particular position of the floating piston therein.

Another object of the invention is to provide simple, practical and effective recoil and counter-recoil mechanism so constructed and arranged as to operate efficiently and furthermore so constructed and arranged that the hydraulic and pneumatic fluids are confined in the system and are merely shifted or displaced from one part of the system to another during the recoil and counter-recoil actions.

Further objects of the invention will appear from the following specification taken in connection with the drawing which forms a part of this application, and in which

Fig. 1 is a longitudinal sectional elevation of mechanism constructed in accordance with the invention, the parts being shown in battery or firing position;

Fig. 2 is a view similar to Fig. 1 but showing the parts in recoil position;

Fig. 3 is a vertical sectional elevation taken substantially on line 3—3 of Fig. 1;

Fig. 4 is a vertical sectional elevation taken substantially on line 4—4 of Fig. 2;

Fig. 5 is a longitudinal sectional elevation of the counter-recoil cylinder; and

Fig. 6 is a longitudinal sectional elevation of the recoil cylinder.

The invention briefly described consists of a system and mechanism comprising a recoil cylinder, a counter-recoil cylinder, a recuperator cylinder and conduits and valve controlled passages between these parts so constructed and arranged that when the gun is fired the liquid will be transferred to a large extent from the recoil cylinder into the recuperator cylinder causing gas under pressure in the recuperator cylinder to be further compressed by the action of the liquid against a floating piston therein. After the gun and parts attached thereto have come to rest in the recoil position the compressed gas in the recuperator cylinder forces the hydraulic medium or liquid back into the counter-recoil cylinder and from this cylinder into the recoil cylinder where the liquid under pressure acts on the head of the recoil cylinder to return the gun recoil cylinder, recuperator cylinder and parts carried thereby to their initial or battery position.

Further details of the invention will appear from the following description.

10 designates a gun to which are affixed yokes 11, 11 slidably supported on a track 12 which is a part of a cradle, the rear end 13 of which extends downwardly to fixedly support the closed end of a counter-recoil cylinder 18. The cradle is pivotally supported intermediate its length by trunnions 14. A recoil cylinder 15, in axial alignment with the counter-recoil cylinder 18, is supported to slide with the yokes 11, 11.

17 is a recuperator cylinder supported in the lower ends of the yokes 11, 11 below the recoil and counter-recoil cylinders. 45 is a floating piston in the cylinder. 19 is a stuffing-box collar surrounding the counter-recoil cylinder 18, threaded into the end of recoil cylinder 15 and arranged to hold a packing 20 between its end and an annular flange 21 in the recoil cylinder.

An enlargement of the end of the counter-recoil cylinder forms a hollow piston 23 which fits in the recoil cylinder. In the end of this piston is a perforated disk 24. 25 is a valve within this hollow piston pressed against a seat 26 by a spring 27 interposed between the disk 24 and an interrupted shoulder 28 on the valve. The recoil and counter-recoil cylinders are filled with oil or other suitable liquid and this valve permits the oil to flow from the counter-recoil cylinder into

the recoil cylinder through the disk 24, but checks its flow in the opposite direction.

30 is a hollow piston rod supported in a boss 31 on the closed end of the recoil cylinder 15. 32 5 is a piston on its other end which fits and slides in counter-recoil cylinder 18.

The recoil cylinder 15 is provided with longitudinally extending internal grooves 33 which are tapered longitudinally either in width or in 10 depth. The counter-recoil cylinder 18 is also provided with similar longitudinally extending grooves 34 tapered in a like manner.

The left hand yoke 11 viewing Figs. 1 and 2 is provided with a valve chamber 35 which 15 communicates with an annular chamber 36 formed at one end of the recoil cylinder between the piston 23 and the packing 20 and also communicates at its lower end with one end of the recuperator cylinder 17. A perforated disc 37 is disposed 20 between the valve chamber 35 and the cylinder 17 and a spring 38 seats against the disc 37 and normally forces a check valve 39 upwardly 25 against a seat 40.

The valve chamber 35 also communicates with 25 a conduit 41 which is fixed in the yokes and has a curved end 42 connected to the head of the recoil cylinder 15 and communicating with the hollow piston rod 30.

A suitable inert gas or air is forced under pressure into the recuperator cylinder 17, to the 30 right of floating piston 45, and the remaining parts of the system, namely, the recoil and counter-recoil cylinders, conduit 41, hollow piston rod 30, valve casing 35 and connecting parts are all 35 filled with a suitable liquid. The initial pressure of the gas in the recoil cylinder is predetermined by the requirements of the system and may be approximately 1500 pounds. It will be understood, however, that this pressure will be varied 40 according to the conditions encountered. Sufficient pressure is used to overbalance the gun barrel and the parts movable therewith and to return them to battery position after firing, even when raised to high elevations. The floating piston 45 may be initially positioned as shown in 45 Fig. 1, anywhere between the ends of the recuperator cylinder. During the recoil action this piston is moved to a position such as that shown in Fig. 2, thus compressing the gas behind 50 it. The exact position of the piston is not material to the operation of the system provided it is at no time located at either extreme end of the cylinder.

A brake or counter-recoil buffer is provided for 55 absorbing the energy of the counter recoil and for the purpose of bringing the gun to rest without jar or shock at the end of the counter-recoil. This brake may be of any desired construction and in the form of the invention illustrated 60 comprises a friction brake band 50 which is carried by a bracket 51 secured to the cradle under the guideway 12. The brake band encircles the recoil cylinder 15 and frictionally engages the outer surface thereof, thus acting to absorb the energy 65 of counter-recoil and prevent jars or shocks.

The operation of the recoil and counter-recoil mechanism above described will now be outlined.

Recoil action

70 Before detailing this action attention is called to the fact that the guideway 12 and the counter-recoil cylinder 18 are supported on the trunnions 14 and are fixed and immovable and that the remaining parts, including the recoil cylinder 75 15, recuperator cylinder 17, conduit 41, hollow

piston rod 30 and parts carried thereby move with the gun 10 and yokes 11 relative to the guideway and the counter-recoil cylinder 18.

The parts are shown in Fig. 1 in battery or firing position, most of the hydraulic medium 5 being located in the counter-recoil cylinder 18, recoil cylinder 15, hollow piston rod 30, and conduit 41 and in the left hand end of the recuperator cylinder 17.

When the gun fires the "kick" or rearward velocity and pressure are absorbed by the recoil mechanism. This pressure causes the gun and parts connected thereto to move from the position shown in Fig. 1 to the position shown in Fig. 2. During this movement the liquid in the 10 recoil cylinder 15 to the right of the piston formed by the enlarged end 23 of the counter-recoil cylinder 18, passes through the longitudinal grooves 33 to the left of the piston 23 and thence through the annular space 36 and valve casing 35 into 15 the left hand end of the recuperator cylinder 17 viewing Figs. 1 and 2. The pressure of this liquid 20 will open the valve 39. As this liquid passes into the recuperator cylinder 17 the floating piston 45 will be forced toward the right viewing Figs. 1 25 and 2, thus compressing the gas to the right of piston 45. This operation will continue until the parts have reached the full recoil position shown in Fig. 2.

During this operation most of the liquid in 30 recoil cylinder 15 (Fig. 1), will be transferred to recuperator cylinder 17 (Fig. 2). The grooves 33 are tapered to offer increasing resistance to the passage of liquid around piston 23 during this movement. Piston 23 passes beyond the right 35 hand end of the grooves and arrests this recoil movement. It is to be noted that during the recoil movement the valve 25 is closed. The counter-recoil cylinder has practically no effect in retarding the recoil as the liquid passes around the piston 32 through the grooves 34 which are of sufficient area to substantially balance the pressure of the oil on both sides of piston 32 during recoil.

Counter-recoil mechanism

After the parts have reached the position shown in Fig. 2 the pressure of the gas in the recuperator cylinder 17 will force the floating piston 45 to the left causing the liquid in the recuperator cylinder to pass into the valve casing 35 and thence through the conduit 41 and hollow piston rod 30 into the counter-recoil cylinder 18. During this operation the valve 39 is closed. The liquid then passes through the grooves 34 of the counter-recoil cylinder 18 to the opposite side of the piston 32 on the end of piston rod 30 and the pressure of this liquid will move the valve 25 from its seat 26 permitting the liquid to pass through the perforated plate 24 into the recoil cylinder 15. The pressure of this liquid in the recoil cylinder will act on the closed head of this cylinder to force the recoil cylinder to the right on the counter-recoil cylinder until the parts have again reached the battery or firing position shown in Fig. 1. The grooves 34 diminish in area from left to right. This results in permitting liquid to pass very freely around piston 32 at first, but the grooves gradually restrict this passage of the liquid and are finally closed by the piston at the end of the counter-recoil movement.

From the foregoing description it will be seen that practical and effective means have been designed for controlling the recoil and counter-recoil action of a gun and that the mechanism and

system have been so worked out that the maximum pressure developed, that between piston 23 and the closed end of the recoil cylinder, after piston 23 has passed over the ends of grooves 33 (Fig. 2) is confined to the recoil cylinder and is not communicated throughout the system. Furthermore, the system described is a closed system in which the liquid and gas are confined within the parts of the apparatus or mechanism and are merely shifted during the action of the recoil and counter-recoil movements. Particular attention is called to the fact that in the system and mechanism described the packing 20 is the only packing used, whereas in other mechanism of the hydro-pneumatic type a plurality of packings are used which are subjected to high pressures. Moreover, in the mechanism used in this invention the packing is subjected only to relatively low pressures and not to the high pressures encountered in the recoil cylinder.

Although one specific embodiment of the invention has been particularly shown and described it will be understood that the invention is capable of modification and that changes in the construction and in the arrangement of the various cooperating parts may be made without departing from the spirit or scope of the invention, as expressed in the following claims.

What I claim is:

1. Recoil and counter-recoil mechanism for guns comprising a stationary counter recoil cylinder, a recoil cylinder fixed to the gun slidable over the counter-recoil cylinder during the recoil of the gun, a piston fixed to the counter-recoil cylinder and disposed in the recoil cylinder, a piston fixed to the recoil cylinder and disposed in the counter-recoil cylinder, a recuperator cylinder, and conduits establishing communication between the inner end of the recoil cylinder and recuperator cylinder, said conduits establishing communication to the inner end of the recoil cylinder throughout the recoil of the gun and during the counter-recoil of the gun between the recuperator cylinder and counter-recoil cylinder and means for establishing communication between the counter-recoil cylinder to the recoil cylinder.
2. Recoil and counter-recoil mechanism for guns comprising a counter-recoil cylinder, a recoil cylinder slidable over the counter-recoil cylinder, a piston fixed to the counter-recoil cylinder and disposed in the recoil cylinder, said piston having a passage therethrough and a valve controlling said passage and opening toward the recoil cylinder and away from the counter recoil cylinder, a piston fixed to the recoil cylinder and disposed in the counter-recoil cylinder, a recuperator cylinder, and conduits establishing communication between the recoil cylinder and recuperator cylinder and between the recuperator cylinder and counter-recoil cylinder and conduits establishing communication between the counter-recoil and recoil cylinders.
3. Recoil and counter-recoil mechanism for guns comprising a stationary counter-recoil cylinder, a recoil cylinder fixed to the gun and slidable over the counter-recoil cylinder during the recoil of the gun, a piston fixed to the counter-recoil cylinder and disposed in the recoil cylinder, a piston fixed to the recoil cylinder and disposed in the counter-recoil cylinder, said last named piston being carried by a hollow piston rod fixedly secured to the recoil cylinder, a recuperator cylinder, and conduits establishing

communication between the inner end of the recoil cylinder and recuperator cylinder during the recoil of the gun and between the recuperator cylinder and counter-recoil cylinder through said hollow piston rod during the counter-recoil of the gun and means for establishing communication through the piston on the counter-recoil cylinder from the counter-recoil cylinder to the recoil cylinder.

4. Recoil and counter-recoil mechanism for guns comprising a stationary counter-recoil cylinder, a recoil cylinder fixed to the gun and slidable over the counter-recoil cylinder during the recoil of the gun, a piston fixed to the counter-recoil cylinder and disposed in the recoil cylinder, said piston having a passage therethrough and a valve controlling said passage, a piston fixed to the recoil cylinder and disposed in the counter-recoil cylinder, said last named piston being carried by a hollow piston rod fixedly secured to the recoil cylinder, a recuperator cylinder, and conduits establishing communication between the recoil cylinder and recuperator cylinder and between the recuperator cylinder and counter-recoil cylinder and conduits establishing communication between the counter-recoil and recoil cylinders.

5. In recoil and counter-recoil mechanism for guns, a stationary counter-recoil cylinder, a recoil cylinder fixed to the gun and slidable in telescoping relation thereto, a piston in the recoil cylinder fixed relative to the counter-recoil cylinder, said piston having an opening establishing communication between said cylinders, a valve for controlling said opening and arranged to open toward the recoil cylinder and away from the counter recoil cylinder, and a piston in the counter-recoil cylinder fixed relative to the recoil cylinder.

6. In recoil and counter-recoil mechanism for guns, a stationary counter-recoil cylinder, a recoil cylinder fixed to the gun and slidable in telescoping relation thereto, a piston carried by one end of the counter-recoil cylinder disposed in the recoil cylinder, said piston having an opening establishing communication between said cylinders, a valve for controlling said opening and arranged to open toward the recoil cylinder and away from the counter recoil cylinder, a piston rod fixed to the recoil cylinder and extending into the counter-recoil cylinder, and a piston on said rod in the counter-recoil cylinder.

7. In recoil and counter-recoil mechanism for guns, a counter-recoil cylinder, a recoil cylinder slidable in telescoping relation thereto, a piston in the recoil cylinder fixed relative to the counter-recoil cylinder, a piston in the counter-recoil cylinder fixed relative to the recoil cylinder, each cylinder having internal longitudinal extending grooves permitting passage of the liquid around said pistons, a recuperator cylinder, means for conducting fluid from the recoil cylinder to the recuperator cylinder, and means for conducting fluid from the recuperator cylinder to the counter-recoil cylinder.

8. Recoil and counter-recoil mechanism for guns comprising a counter-recoil cylinder, a recoil cylinder in telescoping relation thereto, a recuperator cylinder, pistons in said cylinders, a valve casing communicating with the recoil cylinder and with the recuperator cylinder, a valve in the casing arranged to open to permit the passage of fluid from the recoil cylinder through the casing and into the recuperator cyl-

inder, and a conduit leading from said casing to the counter-recoil cylinder through the piston therein.

9. In recoil and counter-recoil mechanism for guns, a recoil cylinder fixed to the gun, a counter recoil cylinder movable into the recoil cylinder, a piston formed on the end of the counter-recoil cylinder and disposed in the recoil cylinder, a packing between the end of the recoil cylinder and surrounding the counter-recoil cylinder, a passage through the piston into the recoil cylinder from the counter-recoil cylinder, a valve seating in a direction toward the counter-recoil cylinder for controlling said passage, a hollow piston rod connected to and extending through the end of the recoil cylinder, a piston on said rod in the counter-recoil cylinder, a recuperator cylinder, and means connecting the hollow piston rod to the recuperator cylinder.
10. A gun, a recoil cylinder affixed thereto, a stationary counter-recoil cylinder having a piston at one of its ends within the recoil cylinder, a recuperator cylinder movable with the recoil cylinder, a one-way passage from the inner end of the recoil cylinder to the recuperator cylinder, and an independent passage from the recuperator cylinder back to the recoil cylinder through the counter-recoil cylinder.
11. A gun, a recoil cylinder affixed thereto, a

stationary counter-recoil cylinder having a piston at one of its ends within the recoil cylinder, a check-valve controlled passage through said piston, a recuperator cylinder movable with the recoil cylinder, a one-way passage from the inner end of the recoil cylinder to the recuperator cylinder, and means for transferring liquid back to the recoil cylinder comprising an independent passage from the recuperator cylinder to the counter-recoil cylinder and through said check-valve controlled passage.

12. A gun, a recoil cylinder affixed thereto, a stationary counter-recoil cylinder having a piston at one of its ends within the recoil cylinder, a check-valve controlled passage through said piston, a recuperator cylinder movable with the recoil cylinder, a one-way passage from the inner end of the recoil cylinder to the recuperator cylinder, and a passage from the recuperator cylinder to the counter-recoil cylinder comprising a hollow rod extending through the recoil cylinder into the counter-recoil cylinder arranged to form an independent means for transferring liquid from the recuperator cylinder back to the recoil cylinder through the counter-recoil cylinder and through said check-valve controlled passage.

GREGORY C. DAVISON.
